UNITED STATES PATENT OFFICE.

HARRY RAFLOVICH, OF BUFFALO, NEW YORK.

DESIGN FOR A TIRE.

58,198.

Specification for Design. Patented June 21, 1921.

Application filed December 18, 1920. Serial No. 431,779. Term of patent 7 years.

To all whom it may concern:

Be it known that I, HARRY RAFLOVICH, a citizen of the United States, residing at Buffalo, in the county of Erie and State of New York, have invented a new, original, and ornamental Design for a Tire, of which the following is a specification, reference being had to the accompanying drawing, forming part thereof, and in which—

Figure 1 is a face view of a tire embodying my new design. Fig. 2 is a cross section of the same, taken on line 2—2, Fig. 1.

I claim:

The ornamental design for a tire, as shown.

HARRY RAFLOVICH.
